(57) **CLAIM**

The ornamental design for a mouthguard, as shown and described.

DESCRIPTION

FIG. 1 is a front view of a mouthguard showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is an exploded, top perspective view thereof;

FIG. 8 is an exploded, bottom perspective view thereof;

FIG. 9 is another exploded, bottom perspective view thereof;

FIG. 10 is another exploded, top perspective view thereof;

FIG. 11 is an enlarged view of an encircled portion, FIG. 11 in FIG. 7; and,

FIG. 12 is an enlarged view of an encircled portion, FIG. 12 in FIG. 8.

The even dashed broken lines depict portions of the mouthguard that form no part of the claimed design. The dash-dot-dot broken lines illustrate the boundary lines of the enlarged portion views of FIGS. 11 and 12 and form no part of the claimed design.
